UNITED STATES PATENT OFFICE

106,131

DESIGN FOR A FLOWER HOLDER OR SIMILAR ARTICLE

Louis A. Butler, East Cleveland, Ohio

Application April 7, 1937, Serial No. 68,593

Term of patent 3½ years

To all whom it may concern:

Be it known that I, Louis A. Butler, a citizen of the United States, residing at 13318 First Avenue, in the city of East Cleveland, county of Cuyahoga, and State of Ohio, have invented a new, original, and ornamental Design for a Flower Holder or Similar Article, of which the following is a specification, reference being had to the accompanying drawing, forming a part thereof.

The Figure 1 is a front view of the holder showing my new design.

view.

I claim:

The ornamental design for a flower holder or similar article substantially as shown.

LOUIS A. BUTLER.
